UNITED STATES PATENT OFFICE.

FREDERICK LILLICH, OF PHILADELPHIA, PENNSYLVANIA.

FENDER.

1,222,877.

Specification of Letters Patent. Patented Apr. 17, 1917.

Original application filed November 15, 1915, Serial No. 61,547. Patent No. 1,187,750, dated August 8, 1916.
Divided and this application filed February 28, 1916. Serial No. 80,791.

To all whom it may concern:

Be it known that I, FREDERICK LILLICH, a citizen of the United States, residing at Philadelphia, in the county of Philadelphia 5 and State of Pennsylvania, have invented certain new and useful Improvements in Fenders, of which the following is a specification.

My invention relates to improvements in 10 fenders, and more particularly to a fender for automobiles, an object of the invention being to provide an improved construction of wheel guard connected to and operated in connection with a pick up fender having 15 improved means for holding the guards and fender in an elevated position and permitting their release and fall to operative position.

The present application is a divisional application of my invention filed November 20 15th, 1915, and bearing Serial No. 61,547, Patent #1,187,750, issued Aug. 8, 1916.

A further object is to provide wheel 25 guards with improved shoes projecting forwardly from the lower ends of the wheel guards and having flexible elastic coverings which prevent any possibility of the arm or other part of a person from passing under the guard.

30 A further object is to provide an improved protecting fender for the radiator of the automobile having a movable section to permit access to the radiator to allow cranking in the ordinary way.

35 A further object is to provide a bell or other alarm which is automatically sounded when the wheel guards and pick-up fender fall to operative position.

A further object is to provide improvements of the character stated which are so arranged and which operate in combination to prevent any portion of the automobile 40 from striking a person or object and reduce to a minimum any possibility of injury.

45 With these and other objects in view, the invention consists in certain novel features of construction and combinations and arrangements of parts as will be more fully hereinafter described and pointed out in the

50 claims.

In the accompanying drawings:

Figure 1 is a view in elevation of the front end of an automobile showing my improvements in position thereon, parts of the

fender structure being broken away to illustrate details. 55

Fig. 2 is an enlarged fragmentary detail view showing the forward edge of the fender supporting mechanism.

Fig. 3 is an enlarged detail view partly in 60 elevation and partly broken away illustrating the mounting of one of the wheel guards and the fender holding mechanism.

Fig. 4 is a top plan view, parts of the fender and automobile being broken away 65 to illustrate details.

Fig. 5 is a view in transverse section through the front axle showing the protecting casing thereon.

Fig. 6 is an enlarged fragmentary detail 70 view partly in elevation and partly in section illustrating the means on the tripping fender for releasing the fender holding catch.

Fig. 7 is an enlarged fragmentary view 75 in section on the line 7—7 of Fig. 3.

Fig. 8 is a view in side elevation showing the mounting of the wheel guards and co-operating parts, the automobile being illustrated in dotted lines, and certain features 80 of the fender omitted for purposes of clearness.

Fig. 9 is an enlarged fragmentary sectional view taken through the axle 6 and showing certain fender holding elements 85 which I employ.

Fig. 10 is a view in longitudinal section through the center of one of the wheel guards.

Fig. 11 is a detail view showing on an 90 enlarged scale the bumper and trip fender mounting, and the fender holding mechanism connected therewith.

Fig. 12 is a view in side elevation illustrating the mounting of the bumper and 95 tripping fender, and also the protecting means for the radiator and the automobile.

Fig. 13 is an enlarged detail view illustrating the projecting foot on one of the wheel guards, the view being taken in section on the line 13—13 of Fig. 10, only a portion of the covering being shown and the spring tongue broken away. 100

Fig. 14 is a detailed view illustrating the manner of connecting the chain to the shoe 105 of one of the wheel guards.

1 represents an automobile having the ordinary frame 2. 3 represents the wheels of

the automobile, the front wheels being mounted on the ordinary stubs 4 which are fixed to forks 5 on front axle 6. To both of the forks 5 on the front axle, I secure rings 5 7 by means of brackets 8, so that the rings 7 are held against movement.

Rings 9 are mounted to turn on the periphery of the stationary rings 7 and bars 10 are secured to the outer rings 9 and support my improved wheel guards 11.

The structure of each wheel guard and its coöperating parts is precisely the same, and the description hereinafter of one will apply alike to both.

15 The wheel guard at its lower end is provided with a shoe 12 which is preferably of relatively heavy rubberized cloth or similar fabric and is supported by a frame 13 secured to the guard 11. This frame 13 and 20 the shoe 12 of which the frame is a part, projects in a general forward direction and constitute a scoop to pick up the arm or leg of a person on the ground and prevent the same from passing into engagement with the 25 wheel.

As a further protection, the shoe 12 has an apron 14 which hangs all around the frame 13, and is held in normal position by a spring tongue 15. This spring tongue 15 30 is pivotally connected to frame 13 as shown clearly in Fig. 13. That is, to say, a transverse pin 16 is projected through the frame, and the tongue 15 is pivotally mounted on the pin and is provided with coiled springs 35 17 which tend to hold the tongue in a general forward direction and return the same to such position in the event the shoe comes in contact with a hard or immovable part of the pavement.

40 The guard 11 is provided on one side with an arm 18 which strikes against the side of the wheel when the guard receives a lateral blow, preventing breaking of the guard and an arm 19 which is secured to the guard is 45 adapted to engage the fork 5 and limit the downward movement of the guard. In Fig. 8 the two positions of the guard are shown, and this feature of the arm 19 is clearly indicated.

50 A shaft 20 is mounted in bearings 21 on the front face of front axle 6, and is provided at its ends with crank arms 22. These crank arms, at their free ends, are provided with sleeves 23 in which laterally projecting pins 24 are mounted, and are provided at 55 their free ends with eyes 25 receiving downwardly projecting pins 26 on the lower bars 10, so that when the shaft is turned it causes the bars 10 and movable rings 9 to move 60 and elevate or lower the guards 11 as the case may be.

An upwardly projecting crank arm 27 is fixed to shaft 20, and carries a catch 28 adapted to engage a stationary catch mem- 65 ber 29, the latter fixed to a clamp 30 secured

to axle 6. The movable and stationary catch members 28 and 29 have beveled ends so that they can readily ride into locked engagement, and when in locked engagement, hold the guards in an elevated position as shown in full lines in Fig. 8.

A scoop fender 31 is connected at one end to the axle 6, at its ends to the guards 11, and is provided at its lower edge with a chain 32 which is connected at its ends 75 to spring-pressed fingers 33 carried by the frames 13 of guards 11.

It will therefore be noted that when the wheel guards 11 are held in an elevated position by means of the catch 28, the scoop 80 fender 31 will likewise be elevated. The catch member 28 is pivotally connected to a bar 34 which is mounted to slide in a slot 35 in arm 27. A spring 36 connects the latch 28 with arm 27 and draws the latch 85 downwardly into its normal holding position.

A shoulder 37 on the bar engages the arm and limits the movement of the bar in one direction. A spring bolt 38, carried by arm 90 27, engages in either of a pair of notches 39 and 40 respectively in the lower edge of bar 34, and a coiled spring 41 is located between a lug 42 on bar 34 and the arm 27 tending to move the bar in a direction to 95 press the shoulder 37 against the arm 27. A stop 43 on bar 34 limits the movement of the bar in the opposite direction.

By means of this arrangement of bar 34 and coöperating parts, the position of the 100 wheel guards and scoop fender can be adjusted or varied in accordance with the condition of the road over which the vehicle is moving which will be more fully hereinafter described.

105 A cable 44 is connected to the free end of arm 27, and is operated by a lever or other suitable device 45 to turn shaft 20 and move the fender to elevated position, so that the catch 28 can engage member 29 and hold the 110 fender in this position.

To release the catch member 27 from engagement with the fixed catch member 29, I provide an angle lever 46 which is pivotally connected at its angle to clamp 30 by means 115 of a pivot bolt 47. One end 48 of this angle lever projects under the catch member 28, so that when the angle lever is moved in one direction, it will lift the catch member 28 far enough to release it from member 29. 120

A cable 49 connects the lever 48 with a foot pedal 50, so that when the latter is operated, the catch 28 can be released. A cable 51 is connected to the spring-pressed bolt 38, and terminates in a handle 52 which can be 125 moved by the operator to release the bolt 38 from engagement with one of the notches 39 or 40.

With the parts as shown in Figs. 9 and 11, the wheel guards are in their highest posi- 130

tion. If it is desired to lower them slightly, it is simply necessary to exert a pull on the cable 51, drawing the bolt 38 out of notch 39, when the weight of the wheel guards and connected parts will cause the arm 28 to swing in a direction to move notch 40 into register with bolt 38, when the operator can release cable 51 and allow the bolt 38 to spring into the notch 40.

10 To return bar 34 to the position shown in Figs. 9 and 11, it is simply necessary while the catch 28 is disengaged from member 29 to exert a pull on the bolt 38.

15 As soon as the bolt 38 is released from notch 40, spring 41 will move the bar 34 longitudinally until shoulder 37 strikes arm 27. When the bolt 38 is released, it will spring into notch 39, and hold the parts in such position of adjustment.

20 A downwardly projecting arm 53 on angle lever 46 is provided with a transverse eye-bolt 54, one end of which is connected by a coiled spring 55 with a fixed arm 56 on clamp 30. This spring 55 holds the lever 46 in normal position, and returns it to such position when cable 49 is released.

25 A pair of brackets 57 are bolted to the forward end of the automobile frame 2, and support my improved bumper rod 58 as 30 will now be explained.

The brackets 57 have tubular portions 59 into which forked members 60 telescope. These members 60 have screw-threaded bolts 61 thereon extending through openings 62 35 in the angle brackets 57, and provided with nuts 63 to adjust the said members.

Coiled springs 64 in the tubular portions 40 of the brackets 57 exert an outward pressure on the members 60, and cushion the bumper rod as will be apparent. The outer ends of the members 60 are bifurcated and links 65 are pivotally connected in the bifurcated outer ends of the members 60 by means 45 of pins 66, and said links 65 at their forward and lower ends, support the bumper rod 58. This bumper rod is held in its forward normal position by means of relatively strong coiled springs 67 which are positioned between the bumper rod and brackets 68 secured to frame 2. These springs 67 sustain 50 the initial shock of impact of bumper rod 58.

The pivotal movement of each link 65 is limited by a lug 65^a on the under face of the bar 60, which is engaged by the link 65, so that springs 64 are compelled to sustain 55 the greater portion of the shock.

A finger 69 on the upper end of one of the links 65 is connected by a cable 70 with a cable 71, the last-named cable being secured 60 to the eye-bolt 54, so that when the bumper rod 58 is moved inwardly to cause the link 65 to pivot, the lever 46 will be moved so as to release the catch 28.

65 The bumper 58 supports a tripping fender 72 which is pivotally connected to the bar

at its upper end by means of collars 73, and is made preferably of two sections 74 and 75 which are adjustably connected by bolts 76 so as to permit the tripping fender a vertical adjustment.

70 The two sections 74 and 75 of the tripping fender have slots 77 to receive the bolts 76, and limit the movement of the sections relative to each other, and I would have it understood that this connection is a loose one, 75 so that the lower section 75 can be easily elevated as will be hereinafter pointed out.

Coiled springs 78 around the rod 58 exert a pressure on the tripping fender 72, holding the latter in its forward position, and 80 chains 79 connect the tripping fender with links 65, and limit the forward movement of the tripping fender, allowing of a certain amount of adjustment by positioning the various links of the chain on hooks 80 on 85 the links 65.

The tripping fender 72 is provided with an arm 81 having a pivoted spring-pressed dog 82 engaging under a hook 83 which is slidably connected to one of the members 60 by means of a pin 84 which extends 90 through a slot in the hook 83 and limits its movement.

The cable 71 above referred to is secured to this hook 83, so that when the hook is elevated by the rearward pivotal movement of the tripping fender, it will move the lever 46 to release catch 28, hence when the tripping fender strikes a person or object, it will be moved rearwardly and cause the release of catch 28 and the fall of wheel guards 100 11 and scoop fender 31 as will be readily understood.

To enable the operator on the vehicle to 105 elevate the tripping fender 72, I have shown cables 85 which connect to the lower section 75 of the tripping fender, and are operated by a single cable 86 which terminates close to the driver's seat 87, and which when given a pull will cause the lower section 75 110 110 to elevate. This is desirable when moving over rough roads, but in ordinary travel over city streets there is no necessity of elevating the lower section of the tripping fender.

A protector 88 is positioned in front of the radiator 89 of the automobile. A protector 90 is located in front of the axle 6, and a protector 91 is positioned above the bumper rod 58.

120 The protector 88 is cushioned by springs 92, and is movably connected to the frame 2 by means of bolts 93 which extend through slots 94 in the frame of the protector 88.

A hinged gate 95 is connected to the protector 88 and is movable so as to permit access to the front of the radiator or to the ordinary crank (not shown) for starting the engine.

125 The protector 90 is cushioned by springs 130

96 located around bolts 97 which connect the ends of the protector with brackets 98 on the upper and lower faces of the axle 6 (see Fig. 5). The protector 91 is of the 5 same length or transverse dimension as the bumper rod 58, and is secured to the front end of the frame in front of the radiator.

As a matter of fact, the rod 58 is utilized 10 as a connecting means for the netting, constituting a part of the protector 91.

The several protectors and fenders above described are preferably formed of similar netting, which is sufficiently strong to withstand the shocks and jolts to which they 15 are necessarily subjected, and I have not described in detail these several nettings, because I consider myself at liberty to use any form of netting which is adapted for the purpose.

26 In Fig. 8, I illustrate an electric bell 99 connected in electric circuit with a battery or other electricity source 100, having a switch 101 which is normally opened, but which is connected by a cord 102 with cable 25 44, so that when the wheel guards and scoop fender fall, they will cause the switch 101 to close the electric circuit and sound the bell.

It will therefore be noted that with my 30 improvements the wheel guards 11 and scoop fender 31 can be dropped by the driver of the automobile by operating foot lever 50 or they will be automatically dropped when the bumper 58 or tripping fender 72 strikes 35 a person or object, hence the fender is operated either manually or automatically.

Various slight changes might be made in the general form and arrangement of parts described without departing from my invention, and hence I do not limit myself to 40 the precise details set forth, but consider myself at liberty to make such changes and alterations as fairly fall within the spirit and scope of the appended claims.

45 Having thus described my invention, what I claim as new and desire to secure by Letters Patent is:

1. The combination with a wheeled vehicle, 50 of wheel guards pivotally connected to the vehicle, a shaft connected to the wheel guards, an arm on the shaft, a catch on the arm engaging a fixed part and normally holding the wheel guards in elevated position, and means for adjusting the catch relative to the arm to vary the elevation of the wheel guards, substantially as described.

2. The combination with a wheeled vehicle, 60 of wheel guards pivotally connected to the vehicle, a shaft connected to the wheel guards, an arm on the shaft, a catch on the arm engaging a fixed part and normally holding the wheel guards in elevated position, a bar supporting the catch and movably connected to the arm, said bar having a 65 plurality of notches therein, and a spring

bolt on the arm adapted to be positioned in any of the notches to vary the elevation of the wheel guards, substantially as described.

3. The combination with a wheeled vehicle, 70 of wheel guards pivotally connected to the vehicle, a shaft connected to the wheel guards, an arm on the shaft, a catch on the arm engaging a fixed part and normally holding the wheel guards in elevated position, a bar supporting the catch and movably connected to the arm, said bar having a plurality of notches therein, and a spring bolt on the arm adapted to be positioned in any of the notches to vary the elevation of the wheel guards, means located adjacent the 80 vehicle seat for moving the arm to elevate the wheel guards, and other means located adjacent the vehicle seat for operating the spring bolt, whereby the elevation of the wheel guards may be adjusted from the seat 85 of the vehicle, substantially as described.

4. The combination of a wheeled vehicle, 90 of wheel guards pivotally connected to the vehicle, and having forwardly projecting frames at their lower ends, and flexible shoes 95 secured to the guards and inclosing the frames, substantially as described.

5. The combination of a wheeled vehicle, 95 of wheel guards pivotally connected to the vehicle, and having forwardly projecting frames at their lower ends, flexible shoes secured to the guards and inclosing the frames, and spring tongues secured to the frames and exerting forward pressure on the lower portions of the shoes, substantially 100 as described.

6. The combination of a wheeled vehicle, 105 of wheel guards pivotally connected to the vehicle, and having forwardly projecting frames at their lower ends, flexible shoes secured to the guards and inclosing the frames, spring-pressed fingers supported by the frames, and a chain connecting the fingers of the respective wheel guards, substantially as described.

7. The combination of a wheeled vehicle, 115 of wheel guards pivotally connected to the vehicle, and having forwardly projecting frames at their lower ends, flexible shoes secured to the guards and inclosing the frames, a scoop fender connected to the wheel guards, means for holding the wheel guards and scoop fender in elevated position, and means for releasing the wheel guards and scoop fender and permitting 120 them to fall, substantially as described.

8. The combination of a wheeled vehicle, 125 of wheel guards pivotally connected to the vehicle, and having forwardly projecting frames at their lower ends, flexible shoes secured to the guards and inclosing the frames, and spring tongues secured to the frames and exerting forward pressure on the lower portions of the shoes, a scoop fender connected to the wheel guards, means for hold- 130

ing the wheel guards and scoop fender in elevated position, and means for releasing the wheel guards and scoop fender and permitting them to fall, substantially as described.

9. The combination of a wheeled vehicle, of wheel guards pivotally connected to the vehicle, and having forwardly projecting frames at their lower ends, flexible shoes secured to the guards and inclosing the frames, spring-pressed fingers supported by the frames, a chain connecting the fingers of the respective wheel guards, a scoop fender connected to the wheel guards, means for holding the wheel guards and scoop fender in elevated position, and means for releasing the wheel guards and scoop fender and permitting them to fall, substantially as described.

10. The combination of a wheeled vehicle, of wheel guards pivotally connected to the vehicle, and having forwardly projecting frames at their lower ends, flexible shoes secured to the guards and inclosing the frames, a scoop fender connected to the wheel guards, means for holding the wheel guards and scoop fender in elevated position, means for releasing the wheel guards and scoop fender and permitting them to fall, and an alarm operated automatically by the dropping of the wheel guards, substantially as described.

11. The combination of a wheeled vehicle, of wheel guards pivotally connected to the vehicle, and having forwardly projecting frames at their lower ends, flexible shoes secured to the guards and inclosing the frames, a scoop fender connected to the wheel guards, means for holding the wheel guards and scoop fender in elevated position, means for releasing the wheel guards and scoop fender and permitting them to fall, and an electric bell included in circuit with a battery and a switch, and means operated by the dropping of the wheel guards causing the switch to close the circuit and sound the bell, substantially as described.

12. The combination with an automobile having pivotally supported forks at the ends of its front axle and having wheels on the stubs of said forks, of rings secured to the forks, other rings mounted to turn on the periphery of the first-mentioned rings, bars secured to the outer rings and holding the latter on the inner rings, wheel guards secured to said bars, means for supporting the wheel guards in elevated position, and means on said bars adapted to engage the forks and limit the downward movement of the wheel guards, substantially as described.

13. The combination with an automobile having a radiator, and a bumper rod at its forward end, of wheel guards in front of the front wheels, a scoop fender connecting the wheel guards, means normally holding the wheel guards and scoop fender in elevated position, an elastically supported fender in front of the radiator, an elastically supported rod positioned above the bumper rod, a netting connecting the said last-mentioned rod with the bumper rod, and a hinged netting gate located above said rod, substantially as described.

14. The combination with an automobile having a radiator, and a bumper rod at its forward end, of wheel guards in front of the front wheels, a scoop fender connecting the wheel guards, means normally holding the wheel guards and scoop fender in elevated position, an elastically supported fender in front of the radiator, an elastically supported rod positioned above the bumper rod, a netting connecting the said last-mentioned rod with the bumper rod, a hinged netting gate located above said rod, and an elastically supported guard in front of the front axle, substantially as described.

In testimony whereof I have signed my name to this specification in the presence of two subscribing witnesses.

FREDERICK LILLICH.
